UNITED STATES PATENT OFFICE.

JESSE D. LYON, OF PITTSBURG, PENNSYLVANIA.

EXPLOSIVE-ENGINE.

SPECIFICATION forming part of Letters Patent No. 738,690, dated September 8, 1903.

Application filed January 28, 1902. Serial No. 91,591. (No model.)

To all whom it may concern.

Be it known that I, JESSE D. LYON, a citizen of the United States, residing at Pittsburg, in the county of Allegheny and State of Pennsylvania, have invented certain new and useful Improvements in Explosive-Engines, of which the following is a specification, reference being had therein to the accompanying drawings, forming part of this specification,

10 in which—

Figure 1 is a central vertical section through my improved gas-engine, the piston and valve being at their lowermost position, showing the circulation of the outgoing products of combustion and the incoming scavenging current of air. Fig. 2 is a partial similar view showing the piston and valve midway. Fig. 3 is a partial similar view showing the piston and valve at the uppermost position. Fig. 4 is an enlarged detail sectional view of a portion of the valve at its lowermost position and illustrating the flow of air to the space between the valve-piston heads. Fig. 5 is a similar view, partly in elevation, illustrating the flow of gas into the same intervening space. Fig. 6 is a cross-sectional view, on an enlarged scale, indicated by the lines VI VI and VI^a VI^a of Fig. 1, the uppermost half of the figure being on the line VI VI, while the lowermost half of the figure is on the line VI^a VI^a at a slightly higher level through the mixture-inlet port. Fig. 7 is a vertical sectional view through the check-valve controlling the inlet-ports, establishing communication from the 25 valve-piston chamber to the combustion-chamber, the section being indicated by the line VII VII of Fig. 6. Fig. 8 is a similar sectional view at right angles to Fig. 7 through the lowermost portion of the valve-chamber 30 and valve indicated by the line VIII VIII of Fig. 6. Fig. 9 is a cross-sectional view through one end of the valve-head and valve-chamber indicated by the line IX IX of Fig. 8.

My invention refers to improvements in explosive-engines of the type known as a "two-cycle" engine, and relates more particularly to the valve for controlling the incoming air and gas and the resultant mixture and the valve-chamber, ports, and valve for controlling and directing the air and gases, together with other details of construction, as shall be more fully hereinafter set forth.

One of the objects is to obviate in a simple manner the necessity of introducing the gaseous fuel into the scavenging charge of air until after the products of combustion have been sufficiently lowered in temperature as to preclude the ignition of the fuel; also, to provide a means for admitting the gaseous fuel after the scavenging of the products of combustion has been completed, obviating the loss of fuel through the exhaust-ports during the scavenging process.

Referring to the drawings, 2 is the main frame of the engine, which is vertical in type, in the upper portion of which is mounted the cylinder 3, having the piston 4 connected with the crank of the engine by the usual piston-rod, cross-head, and pitman, the cylinder and its head also being provided with circulation-chambers, to and from which water is conducted by the inlet and outlet pipes 5 and 6.

Around the lower portion of the cylinder is a chamber 7, into which air is conducted by a pipe 8, provided with a check-valve 9, permitting an inflow of air into the chamber 7 upon the upward stroke of the piston, but preventing its return upon the downstroke.

The chamber 7, at one side of the cylinder, extends upwardly, as shown, and communicates with the interior of the cylinder by a series of ports 10, arranged along one side through the shell of the cylinder on a common level, which level corresponds with and is just above the lowermost level of the top 85 of the piston at the termination of its down-stroke.

On the opposite side of the cylinder, perforating its shell at a slightly higher level, are a series of similar ports 11, communicating with a common exhaust-chamber 12 in the side of the cylinder, from which, by an exhaust-pipe 13, the products of combustion are led outwardly from the engine.

The piston 4 is provided with an upwardly-extending apron or deflector 14, adapted to deliver the scavenging current of air upwardly to the interior of the combustion-chamber and to force out the products of combustion through the ports 11 at the lowermost position of the piston. Such scavenging action will be facilitated by the considerable pressure to which the air in chamber 7 will be raised by the downstroke of the pis-

ton, outwardly seating the check-valve 9 and confining the air in such chamber 7 until the piston has uncovered ports 10, when the air will rush into the interior of the cylinder and will effectually force out of it the burned gases, which have already been reduced in pressure by partial exhaust through the previously-uncovered exhaust-ports 11.

Located at one side of the cylinder 3, either 10 cast integral with it or made in a separate piece, is the valve-cylinder 15, into the upper end of which, either through an extended portion of the cylinder-head or in the top of cylinder 15 itself, is introduced the gas-inlet 15 pipe 16, leading from any source of supply and provided with the check-valve 17, permitting an inflow of gas, but preventing its return. To the lower end of cylinder 15 is connected in a similar manner an air-inlet 20 pipe 18, provided with a check-valve 19, adapted to permit an inflow of air to the lower end of the valve-cylinder, but preventing its return in the same manner.

Mounted in the cylinder and adapted to 25 travel longitudinally therein is the mixture-valve consisting of the two heads 20 20, secured to a piston-rod 21, connected with the cross-head of the engine and adapted to operate in conformity with the stroke of the piston 30 4. The heads of this mixture-valve (shown more fully in Fig. 8 of the drawings) are provided, as shown, with a series of perforating-ports 22, extending longitudinally from one end to the other and covered on the inner end 35 of each head by a check-valve 23. An intervening spring 24, surrounding the stem 21, is adapted to exert pressure in both directions and to normally keep such check-valves seated.

40 Located between the mixture-valve cylinder and the engine-cylinder, mounted in a casing 25, secured to both cylinders, is a check-valve 26, normally held seated by a spring 27, surrounding the valve-stem 28. Leading to 45 the under portion of such check-valve from the middle portion of the mixture-valve chamber is an inlet-port 29, while leading outwardly above the check-valve is another port 30, opening into the cylinder 3 and above the 50 level of the air-inlet ports 10, (more clearly indicated in dotted lines in Fig. 5), which ports and check-valve are for the purpose of admitting the compressed mixture into the combustion-chamber during the upward travel 55 of the engine-piston after the products of combustion have for the most part escaped from the cylinder and have been replaced by the incoming air from chamber 7.

The operation is as follows: On the downward stroke the upper piston-head 20 of the mixture-valve will draw in a charge of gas, filling the upper portion of the chamber 15, and on the upward stroke the same charge will be compressed, while a similar charge of 65 air will be drawn in by the pipe 18, and at the latter portion of the upward stroke the upper check-valve 23 will be forced down by

said compressed body of gas, which will then escape through ports 22 to the interior space intervening between the heads 20, as clearly 70 shown in Fig. 5. On the next downward stroke the air below the lower head 20 will be compressed and will also pass up through ports 22 in the lower head, opening valve 23 and passing into the interior space, as 75 clearly shown in Fig. 4. On the next upward stroke the inclosed mixture, which is thus brought up to a considerable degree of compression between the heads 20, will when the upper head 20 has passed above port 29 escape outwardly through said port, raising check-valve 26 and escaping through port 30 into the interior of the combustion-chamber of cylinder 3 at high velocity in advance of the upwardly-rising piston 4, thereby becoming 80 thoroughly mixed with the body of air therein at lower pressure from chamber 7. The resulting mixture will then be compressed by the piston to the point of ignition, which may be by hot tube, electric spark, or other suitable 85 means. The pressure in the cylinder during combustion and expansion being higher than the pressure of the mixture between the heads 20 does not permit the opening of check-valve 26 during the downstroke of the piston at 90 the point when port 30 is uncovered by the piston in its downward stroke, thereby preventing the premature escape of the mixture into the combustion-chamber. Such premature escape of the mixture is further prevented during the remainder of the downstroke by the upper head 20 covering port 29, thus preventing the mixture from prematurely escaping into the cylinder and mingling with the burned gases and passing out 95 with them through ports 11. At the beginning 100 of the upstroke, simultaneous with the covering of ports 11 and previous to covering of port 30 by piston 4, the upper head 20 will have uncovered port 29, permitting the mixture between the heads 20 to lift check-valve 26 and rush with high velocity through port 30 into the cylinder, forming, with the air therein from chamber 7, a mixture of proportions which will become explosive when brought to 115 proper compression in the combustion-chamber of the cylinder. The piston 4 is provided with an upwardly-extending deflector 14, the purpose of which is to throw the scavenging-current upwardly through the top of the cylinder and forcing downwardly and outwardly 120 the burned gases. As thus constructed and operated it will be observed that the engine is capable of an explosion at each revolution, the operation of taking in the gas and air 125 through the heads of the valve taking place at each up-and-down stroke and to discharge the compressed mixture in the compressing-chamber through port 30 occurring at the termination of each downward stroke of the 130 piston.

It will be understood that suitable governing, lubricating, or other necessary devices may be included in the general construction;

but inasmuch as such do not form any part of the present invention they have not been herein specifically shown or described.

It will be observed that the mixture-valve, by compressing both the gas and air and finally delivering the resulting mixture under considerable pressure to the engine-cylinder, obviates the necessity of a separate compression-chamber independent of the valve mechanism necessary in many forms of gas-engines, and the resulting operation is thereby greatly facilitated.

It will be obvious that the air and gas inlet openings and supply pipes 16 and 18 may be used interchangeably for either air or gas with equally good results; also that any other suitable fuel may be substituted for gas, as hydrocarbon vapor, oil, &c.

Changes and variations may be made by the skilled mechanic in the design, construction, proportions, or other details without departing from my invention, and I desire to include all such as within the scope of the following claims.

25 What I claim is—

1. A gas-engine, provided with a cylinder, an air-compressing chamber exterior to the cylinder and communicating with the interior thereof, exhaust-ports leading outwardly from the cylinder, and a mixture-valve chamber provided with a compressing-valve having check-controlled inlets opening into its interior, and a port leading from the compressing-chamber to the cylinder.

35 2. A gas-engine comprising a cylinder, a piston, an air-compressing chamber exterior to the cylinder and communicating with the interior, a valve-controlled air-inlet for the compressing-chamber, exhaust-ports leading outwardly from the cylinder, and a mixture-valve chamber having independent air and gas supply openings, with a compressing-valve having check-controlled inlets opening into its interior, and a communicating opening from the mixture-valve chamber to the cylinder, substantially as set forth.

3. A gas-engine consisting of a cylinder, a piston, an air-compressing chamber exterior to the cylinder and communicating with the interior, a valve-controlled inlet therefor, exhaust-ports leading outwardly from the cylinder, a valve-chamber communicating with the cylinder, provided with air and gas inlet openings, and a double-headed compressing-valve provided with check-controlled inlets adapted to compress the air and gas at the ends and to inclose the explosive mixture between the heads.

4. A gas-engine consisting of a cylinder, a piston, an air-compressing chamber exterior to the cylinder and communicating with the interior, a valve-controlled inlet therefor, exhaust-ports leading outwardly from the cylinder, a valve-chamber communicating with the cylinder provided with valve-controlled air and gas inlet openings, and a double-

headed compressing-valve provided with check-controlled inlets adapted to compress the air and gas at the ends and to inclose the explosive mixture.

5. A gas-engine consisting of a cylinder, a piston, exhaust-ports leading from the cylinder, a valve-chamber communicating with the cylinder, air and gas ports opening thereinto at each end, a double-headed piston-valve provided with valve-controlled perforations, adapted to compress the air and gas at the ends and to inclose the compressed mixture between the heads and deliver it to the cylinder, and means for igniting the mixture.

6. A gas-engine consisting of a cylinder, a piston, exhaust-ports leading from the cylinder, a valve-chamber communicating with the cylinder, valve-controlled air and gas ports opening thereinto at each end, a double-headed piston-valve provided with valve-controlled perforations, adapted to compress the air and gas at the ends and to inclose the compressed mixture between the heads and deliver it to the cylinder, and means for igniting the mixture.

7. A gas-engine consisting of a cylinder, a piston provided with a piston-rod and cross-head, exhaust-ports leading from the cylinder, a valve-chamber communicating with the cylinder, valve-controlled air and gas ports opening into the valve-chamber at each end, a double-headed piston-valve provided with perforated ports and spring-controlled closures therefor, adapted to compress the air and gas at the ends of the chamber and to inclose the compressed mixture between the heads and to deliver it to the cylinder, a piston-valve rod connected with the cross-head, and means for igniting the mixture.

8. A gas-engine consisting of a cylinder, a piston, exhaust-ports leading from the cylinder, a valve-chamber communicating with the cylinder, an intervening check-valve, air and gas ports opening into the valve-chamber at each end, a double-headed piston-valve provided with valve-controlled perforations, adapted to compress the air and gas at the ends of the valve-chamber and to inclose the compressed mixture between the heads and to deliver it through the check-valve-controlled communication to the cylinder, and means for igniting the mixture.

9. In combination with the cylinder of an explosive-engine: a mixture-chamber communicating therewith, provided with an air-inlet at one end, a gas-inlet at the other end, and a compressing-valve consisting of perforated piston-heads, mounted on a common stem, closures for the perforations, and a spring adapted to keep the closures seated.

10. In combination with the cylinder of an explosive-engine, a mixture-chamber provided with an air-inlet at one end, a gas-inlet at the other end, a valve-controlled passage leading from the chamber to the cylinder, and a compressing-valve consisting of perforated

piston-heads mounted on a common stem, closures for the perforations, and a spring adapted to keep the closures seated.

11. A mixture-valve for explosive-engines consisting of separate piston-heads, longitudinal ports therethrough, disks adapted to cover said ports on the inner ends of the heads, and a spring adapted to exert pressure against the disks.

12. In combination with a cylinder and piston of a gas-engine, a mixture-chamber communicating with the cylinder, and a double-headed compressing-valve therein, provided with perforated ports and inner spring-controlled closures therefor, with means for actuating the valve, whereby its stroke corresponds with the stroke of the piston.

13. A gas-engine consisting of a working cylinder provided with a piston, exhaust, air and mixture ports, an auxiliary mixture-cylinder, a movable compressing-chamber therein, a passage from the mixture-cylinder communicating from the mixture-port with the working cylinder, and a valve in said passage controlled by difference in pressure in the two cylinders, substantially as set forth.

14. A gas-engine consisting of a working cylinder, provided with a piston, exhaust, air and mixture ports, and an auxiliary fuel-compressing cylinder, with a double-headed pis-

ton therein provided with passages through its heads forming communications between the cylinder-spaces at the ends of the piston, and the spaces between the piston-heads, substantially as set forth.

15. A gas-engine consisting of a working cylinder provided with a piston, exhaust, air and mixture ports, and an auxiliary fuel-compressing cylinder, with a double-headed piston therein provided with passages through its heads, and internal check-valves seating upon the inner faces of the two piston-heads, and controlling the passage of gas through such passages, substantially as set forth.

16. A gas-engine consisting of a working cylinder provided with a piston, exhaust, air and mixture ports, and an auxiliary fuel-compressing cylinder, and a moving compressing-chamber having two piston-heads and inclosed in the auxiliary cylinder, provided with inlet-ports through the piston-heads, and spring-controlled check-valves seating upon the inner faces of said piston-heads, substantially as set forth.

In testimony whereof I affix my signature in presence of two witnesses.
